UNITED STATES PATENT OFFICE.

HUGH McCABE, OF LAWRENCE, MASSACHUSETTS.

METHOD OF COLD FLANGING IRREGULARLY SHAPED SHEET-METAL PLATES.

Application filed July 31, 1922, Serial No. 578,590.

To all whom it may concern:

Be it known that I, HUGH McCABE, a citizen of the United States, residing at Lawrence, in the county of Essex and State of Massachusetts, have invented certain new and useful Improvements in Methods of Cold Flanging Irregularly Shaped Sheet-Metal Plates; and I do hereby declare the following to be a full, clear, and exact description of the invention, such as will enable others skilled in the art to which it appertains to make and use the same.

The present invention relates to an improved method of cold flanging irregularly shaped sheet metal plates.

The machine of the McCabe Patent No. 1,006,861, was intended for use, among other things, in flanging circular disks, but the bender face and the cooperating face against which the flange is formed were required to correspond to the curvature which it was desired to give to the flange. With the bender face and cooperating face curved, it is apparent that any given pair of such faces would be adapted only for a single radius of curvature, and while the use of such machine for such purpose accomplished a very substantial saving over the hot flanging of metal plates, the flanging of irregularly shaped plates, such, for example, as the tube sheet of a locomotive fire box, presented a piece of work to which the machine of such patent was not adapted.

In the McCabe Patent No. 1,164,732, the flanging of square corner and fileted corner plates was contemplated by the use of forms which fitted the corners, but it was required that the metal be heated in order to do the work at the corners.

The object of the present invention is to produce a method of cold flanging sheet metal plates without the use of formers especially shaped to the surfaces to be produced and adapted to form flanges on a wide variety of irregularly shaped plates. To the above end the present invention consists in the method hereinafter described and particularly defined in the claims.

In the accompanying drawing, Figure 1 is an elevation and Fig. 2 is an edge view of a fire box tube sheet for locomotive boilers; and Fig. 3 is a sectional plan of a portion of a McCabe cold flanging machine arranged to practice the method herein described.

The present invention as employed in flanging fire box tube sheets for locomotive boilers is described as follows: The tube sheet 1 has a flanged edge with curves of different radius and straight edges at different parts. Thus it has a straight portion A, an ogee portion B, a short radius portion C, and a long radius portion D. The curve is re-entrant at E, which is the lower part of the ogee, and salient throughout the remainder F of the ogee and throughout the short radius and long radius portions. Now, the method is such that it will form the flange on the straight, salient and re-entrant portions of the edge within certain limits without any change in the formers. The work is clamped between upper and lower clamp members 9 and 10. The lower clamp member 10 is a face against which the flange is to be formed, having a radius of curvature corresponding to or less than the radius of curvature of the salient curvature of shortest radius, and a bender 11 provided with a convex flange forming face of a radius of curvature corresponding to or less than the radius of curvature of the re-entrant curvature of shortest radius of the flange to be formed. Thus, the radius of curvature of the convex face of the clamp 10 corresponds to or is less than the salient curvature of shortest radius which, in the particular tube sheet illustrated, would be the salient curvature F, and the curvature of the flange forming face of the bender 11 corresponds to or is less than the radius of curvature of the re-entrant portions of the flange to be formed, which, in the tube sheet illustrated, would be the re-entrant portions E. Furthermore, the face of the bender is made narrow so that short portions of the flange may be operated upon at each bending operation. The clamp is closed on the body portion of the plate to be flanged adjacent to the flange portion, i. e., the portion to be formed into the flange, and while so clamped the adjacent flange portion is operated upon by the bender to form it into a flange. The short radius portions C of the tube sheet are not adapted to be made by the present method. All portions of the flange except the short radius portions C will be formed according to the present method, and then the machine will be provided with a different pair of formers and the short radius portions of the flange will be formed. This

105
110

will be done by providing the machine with a former 10 of shorter radius of convex curvature, which will project further into the flange receiving space of the machine, and by using a bender 11 provided with a face correspondingly shorter, that is, extended a correspondingly shorter distance from the bender segment 12.

In carrying out the invention in its best form the bender 11 will be provided with a sliding bender face 13 which, when it engages the flange portion of the sheet, will remain in contact with the portion which it first engages, and slide in the bender 11 so as thereby to prevent the wiping of the bender face over the surface of the flange being formed. This is a feature of the invention viewed in its more specific aspects.

Another feature which contributes to most perfect form of the invention consists in making the bender face narrower than the face against which the flange is formed. This permits the formation of re-entrantly curved flanges of shorter radius of curvature than would otherwise be possible.

In practicing the present method the flanging machine will be provided with two formers, of which the clamp member 10 is one and the bender 11 is the other. The former 10 will have a radius of curvature corresponding to or shorter than the radius of curvature of the flange to be formed at its point of salient curvature of shortest radius, and the bender will have a radius of curvature corresponding to or less than the radius of curvature of the flange to be formed at its point of re-entrant curvature of shortest radius.

The method will be practiced as follows: Starting at one end of the flange, as at the end 14, the operator will proceed to form partial bends in the flange, working along the edge up to the beginning 15 of the portion C of short radius of curvature. This portion will be passed, and the forming of the flange on the next portion D of the plate will be proceeded with, after which the short radius portion C' will be passed, and the remainder of the edge of the plate will be operated upon. These operations will be continued until the straight, ogee and long radius portions of the flange are formed, after which the plate will be finished at the short radius portions.

The part of the body portion of the plate which is subjected to the clamping action so as to hold it during the formation or partial formation of the flange is shown in Fig. 3, and is indicated by the outline of the lower clamping member 10. It is immaterial, of course, what the shape of the top clamp member may be, because the area effective for holding the plate is the area of the bottom clamp member. This area, it will be observed, is convex to the flange por-

tion at the point where the flange is being formed by the bender. The forming of the flange at the edge of the plate proceeds progressively. First a flange is bent down along successive portions of the edge through a part of the angle through which it is intended finally to be bent. Then the flange is bent down by successive increments through a further angle, and finally the flange is bent down to the final position which it is intended to assume in the finished work. In the final bend imparted to the flange it is pressed against the stationary former surface.

It will be observed that in forming the straight portions A of the disk, the metal will be stretched and compressed along the edge of the flange as the forming proceeds, that in forming the re-entrant portions of the flange the metal of the edge of the plate will be compressed, and that in forming the curved portions the metal will be both stretched and compressed as the forming proceeds. The method is best carried out by use of a straining device such as is shown in McCabe Patent No. 1,408,106, adjustments of the amount of strain to which the plate is subjected during the forming operation being made from time to time as the flanging progresses. Thus throughout the straight portions of the flange a certain adjustment of the amount of strain to which the plate is subjected will be employed, throughout the re-entrant portions of curvature less strain will be employed, and throughout the salient portions of the plate edge a straining of the plate will be employed which will be greater with short radius curves than with long radius curves.

Having thus described the invention, what is claimed is:

1. The method of cold flanging irregularly shaped sheet metal plates having points of salient and re-entrant curvature, which consists in clamping the body portion of the plate adjacent to the flange portion between clamping members, and subjecting the flange portion of the plate to bending pressure between two formers, one of which is provided with a convex face against which the flange is to be formed, having a radius of curvature corresponding to or less than the radius of curvature of the flange at the point of salient curvature of shortest radius, and the other of which is provided with a convex flange forming face of a radius of curvature corresponding to or less than the radius of curvature of the plate at the point of re-entrant curvature of shortest radius.

2. The method of cold flanging irregularly shaped sheet metal plates having points of re-entrant curvature, which consists in clamping successive parts of the body portion of the plate adjacent to the

flange portion between clamping members, and subjecting the successive flange portions of the plate to the action of a narrow faced bender of convex form having a radius of curvature less than the radius of curvature of the plate at its point of re-entrant curvature of shortest radius.

3. The method of cold flanging irregularly shaped sheet metal plates, which consists in clamping successive areas of the body portion of the plate of convex form located tangent to the flange portion at the flange forming point, and subjecting the flange portion of the plate at such point to the bending action of a former which presents a convex face to the flange portion.

4. The method of cold flanging irregularly shaped sheet metal plates, which consists in clamping successive parts of the body portion of the plate over a convex area tangent to the flange forming point, and subjecting a part of the flange portion to the action of a convex bender at such point, and repeating such operations along the edge of the plate.

5. The method of cold flanging irregularly shaped sheet metal plates, which consists in clamping successive parts of the body portion of the plate over an area adjacent and convex to the flange portion of the plate, and subjecting the flange portions opposite the clamped area to the bending action of a flange former.

6. The method of cold flanging irregularly shaped sheet metal plates, which consists in clamping successive parts of the body portion of a plate adjacent to the flange portion between clamping members over areas adjacent to the flanged portion, and subjecting the adjacent flange portion

to the bending action of a convex flange forming face, having provision for engaging and remaining in contact with the surface of the flange portion of the plate during the bending action without slipping. 45

7. The method of cold flanging irregularly shaped sheet metal plates, which consists in clamping a relatively small convex area of the body portion of the plate tangent to the flange portion, and subjecting 50 the flange portion of the plate at such point of tangency to the bending action of a narrow convex flange forming bender.

8. The method of cold flanging irregularly shaped sheet metal plates, which consists in clamping a convex area of the body portion of the plate adjacent to the flanged portion between clamping members, straining the plate, subjecting the plate to the action of the bender for bending a portion of 60 the flange at the point of tangency of the clamping area of the flanged portion, and varying the straining for different portions of the plate depending upon the direction and degree of curvature. 65

9. The method of cold flanging irregularly shaped sheet metal plates, which consists in clamping the body portion of the sheet over a small area tangent and convex to the flange portion and forming the flange 70 by the use of convex faced formers.

10. The method of cold flanging irregularly shaped sheet metal plates, which consists in clamping successive convex areas of the body portion adjacent to the flange portion, and at each clamping operation subjecting the flange portion adjacent thereto to the flange forming action of a convex faced bender. 75

HUGH McCABE.
